TRIMMING

Edward A. Neff, Chicago, Ill., assignor to Phoenix Trimming Company, Chicago, Ill., a corporation of Illinois

Application November 19, 1934, Serial No. 753,584

14 Claims. (Cl. 156—10)

This invention relates in general to a decorative drapery or trimming for framed openings, walls, and the like, and has more particular reference to a cord trimming for window apertures.

An important object of the invention is in the provision of an improved decorative hanging and support used in connection with curtain poles and cord hangings, by means of which new and improved draping effects are produced.

A further object of the invention is in the provision of an improved decorative hanger and support for holding a plurality of cord hangings in a predetermined looped and set position.

A still further object of the invention is in the provision of an enlarged decorative knob structure adapted to be used in connection with curtain poles.

A still further object of the invention is in the provision of improved means for supporting a plurality of drapery cords in a variety of decorative effects.

In the accompanying drawing,

Fig. 1 is a view in elevation illustrating a preferred embodiment of the invention in connection with a curtain pole for a single opening;

Figs. 2 and 3 illustrate various arrangements of the trimming to produce different decorative effects;

Fig. 4 is a front elevation of a supporting button or knob for the trimming;

Fig. 5 is a section of the supporting knob taken on the line 5—5 of Fig. 4; and

Fig. 6 is a perspective of a modified form of holding clip.

In a decorative trimming for windows, doors and the like, it is desirable to support a plurality of drapery cords from a curtain pole or other support and to hold the cords in a predetermined

set or looped position so that they will be properly spaced apart and the ends located at different distances for the desired decorative effect. It is also desirable to hide the joints of the cords and to produce a decorative effect with the supports

for the cords. If the cords are pinned or otherwise supported along the pole, an unfavorable appearance is presented which is objectionable from a decorative standpoint.

The present invention overcomes these objections by providing a knob which is preferably of considerable diameter so that it may be painted or colored to have a decorative effect in itself, it is supported by an ordinary curtain pole, and is provided with means for adjustably securing the drapery or trimming cords in any suitable

position so that the desired decorative effect may be obtained.

Referring now more particularly to the drawing, a framed opening 10 is shown in Fig. 1, which may be either a door, window or the like, over which a curtain pole 11 is supported in any desired or suitable manner, and may have knobs 12 or other end decorations as desired.

To support a drapery or trimming comprising a number of cords 13, 14 and 15 from the curtain pole 11, at least two buttons or knobs 16 are supported from the curtain pole by means of a hanger 17 having a hook 18 to engage over the curtain pole 11 and a bottom hook 19 to engage a plurality of the cords. Each holder 17 is attached 10 to its knob 16 by a fastening screw 20 and by means of a tongue 21 turned at right angles to the holder and adapted to engage in a central recess 22 at the back of the knob or to be pressed into the knob itself so that the holder will not 20 turn or swing with respect to the knob. A central opening 22 is provided in forming the knob or button which is preferably turned upon a lathe or the like, the opening constituting the means for holding the button in forming it. 25

The hook 19 formed in the holder is rather long and narrow in cross section so that it will engage a plurality of the cords in position one above the other, holding the cords in any desired spaced position with the intermediate portions of the cord held in spaced and looped relation between the buttons or knobs 16 as shown in Figs. 1, 2 and 3.

The ends of the cords are commonly provided with tassels, balls 25 or other decorative members which are also variously located by properly arranging the cords at different heights along the sides of the opening.

With this construction the trimming is quickly applied and removed from a curtain pole, the 40 cords are easily varied and held in any desired place by the hook 19 of the holder, as the cords are intended to fit more or less tightly therein, and if compressed in place they will be held tightly against movement in the holder. The upper 45 end of the hook 19 is also located, as shown more clearly in Fig. 5, in a position just below the central portion of the upper hook 18 so that the holder may be pressed in position upon a pole 11 and because of the location of the hook 19 50 the holder and the button 16 is not easily disengaged from the pole 11.

Instead of having a pole engaging hook at the upper end of the holder 17 as shown in Fig. 5, a holder 27 as shown in Fig. 6 may have a straight 55

upper extension 28 with a perforation 29 therein for attaching it by means of a nail or screw to any suitable support, the cord engaging hook 19 being the same and operating in a similar manner, and the hole 30 being provided for attaching it to a button 16.

It is obvious that various combinations of colors, drapery cords, tassels, loops and buttons will produce different decorative effects and the buttons or holders may also be attached out of line with each other as represented in Fig. 3, to engage any suitable support, without departing from the spirit and scope of the invention.

I claim:

- 15 1. In a draping trimming, the combination with a curtain pole, of a plurality of drapery cords, and buttons having means for suspending them from the pole and for engaging the cords to hold them in spaced relation between the buttons.
- 20 2. A trimming comprising buttons and a plurality of drapery cords, and each button having a supporting hanger at the back with an open hook adapted to engage the cords therein in superposed position.
- 25 3. A trimming comprising a plurality of drapery cords, a plurality of decorative supporting buttons, and a single supporting member at the back of each button having a portion to hold the cords therein and to provide means for suspending the button and cords.
- 30 4. A trimming comprising drapery cords, decorative supporting buttons, each button having a supporting member attached at the back thereof and a spring hook portion to yieldingly engage each of the cords therein and another hook portion by means of which the button is suspended, and a supporting pole upon which the buttons are suspended in spaced apart relation, the cords being held in spaced apart looped relation between the buttons.
- 35 5. A drapery trimming comprising a horizontal curtain pole, a plurality of decorative buttons, means attached to each button for suspending it from the pole, a plurality of drapery cords, and resilient hook means at the back of each button to engage the cords yieldingly therein and prevent them from slipping with respect to each other and for maintaining them in spaced and looped position between the buttons.
- 40 6. In a drapery trimming, a plurality of cords, and means for supporting and engaging the cords in superposed relation comprising a decorative button and a metal clip at the back thereof having a hook portion at the top to engage a horizontal pole support and a hook portion at the bottom into which the cords may be slipped one above the other and yieldingly held against slipping therein.
- 45 7. In a drapery trimming, a plurality of cords, a decorative button, a metal clip attached to the

back of the button having a top hook to engage over a curtain pole and a bottom hook to engage the cords therein, and means for preventing the clip from turning with respect to the button.

8. In a structure according to claim 7, a circular button having a back opening, a fastening screw to attach the clip to the button at one side of the opening, and an extension from the clip engaging in the opening to prevent the button and clip from relative turning.

9. A trimming comprising a plurality of drapery cords, decorative buttons, a supporting clip attached to the back of each button and concealed by the button, the clip having an upper hook for engaging a horizontal supporting pole and a lower hook extending below a pole in the upper hook and adapted to engage the cords in superposed position and the button hiding the cords where they come together in the lower hook.

10 10. A trimming comprising a plurality of cords held together at intervals to produce decorative spaced loops, a decorative supporting button therefor, and a clip at the back of each button having a portion for suspending it and another portion for engaging the cords where they are held together and concealing the junction thereof.

11. In a drapery trimming, a decorative button for suspending cords from a curtain pole comprising a flat body with a rounded front, and a hook member extending across the flat back and having an open upper hook to engage a curtain pole for suspending the button and a lower spring hook for yieldingly engaging a plurality of drapery cords therein and holding them against slipping.

12. In a drapery trimming, a plurality of cords and a supporting clip therefor having a hook to engage a horizontal curtain pole, and a lower hook to engage the cords yieldingly therein and prevent them from slipping.

13. In a drapery trimming, a curtain pole, a plurality of drapery cords, and means for suspending the cords in spaced looped condition below the pole, comprising metal clips each having a hook to engage the pole and a lower extension thereof with an open hook portion into which the cords are yieldingly inserted in superposed relation to prevent the cords from slipping with respect to each other.

14. A trimming comprising a plurality of cords held together at intervals to produce decorative loops spaced one above the other, a horizontal pole, and means including metal clips each having an upper hook to engage the pole and a lower hook to engage the cords and hold them yieldingly together to maintain the cords in their intended spaced relations.

EDWARD A. NEFF. 60
